UNITED STATES PATENT OFFICE.

WINNFIELD RUSSEL PENDER, OF HOUSTON, TEXAS.

ATTACHMENT FOR BOILERS.

Application filed April 3, 1923. Serial No. 629,703.

This invention relates to attachments for boilers, and more particularly to air supply indicators for oil fired boilers.

In the present invention, I provide an attachment adapted to be placed in the gas outlet of an oil fired boiler by means of which the operator may determine whether a proper mixture of air and oil is being fed to the boiler.

10 The attachment consists of a light adapted to be arranged on one side of the outlet passage, and a mirror on the opposite side in alignment therewith, together with means for permitting the operator to observe the 15 reflection of the light in the mirror and thus determine the character of the gases passing through the outlet passage.

An object of the invention is the provision 20 of a mirror that may be adjusted without moving the casing of the attachment to cure any defects in the installation of the device or take care of any movement of the boiler walls.

25 A further object of the invention is the provision of means for cleaning the light and mirror to prevent accumulation of soot thereon.

In the accompanying drawings, I have shown several embodiments of the invention.

30 In this showing:

Figure 1 is a horizontal sectional view of the gas outlet of a boiler showing the invention applied,

35 Figure 2 is a front elevation of the mirror casing detached,

Figure 3 is a vertical sectional view on line 3—3 of Figure 2,

Figure 4 is a horizontal sectional view on line 4—4 of Figure 3,

40 Figure 5 is a view similar to Figure 1 showing the method of installing the apparatus on a pair of boilers forming a battery,

Figure 6 is a similar view showing the device applied to the smoke stack,

45 Figure 7 is a detail sectional view on line 7—7 of Figure 6,

Figure 8 is a similar view on line 8—8 of Figure 1, and

50 Figure 9 is a section taken on line 9—9 of Figure 5.

Referring to Figures 1 to 4 of the drawings, the reference numeral 1 designates the walls of a boiler separated from each other to provide a space. The attachment forming the subject matter of the present invention is applied to the boiler adjacent the boiler damper or flue gas outlet. Suitable transverse openings are formed in the boiler wall in alignment with each other, and a pipe or casing 2 is arranged in one of these openings. The outer end of this pipe is threaded for the reception of a mirror casing 3 having a wall 4 disposed substantially at an angle of 45 degrees to the axis of the pipe and forming in effect, an elbow. The opposite end of the mirror casing is threaded for the reception of a sight tube 5. A mirror 6 is mounted in the mirror casing in a holder 7, the mirror being retained in the holder by means of lugs 8. A threaded stem 9 extends from the holder through the wall 4 and a nut 10 is mounted thereon. The threaded stem is best arranged substantially centrally of the mirror holder. The wall 10 is further provided with a plurality of threaded openings for the reception of lugs 11 which bear against the rear face of the mirror holder to permit adjustment thereof.

The sight tube 5 is provided with a plain glass or lens 12 of slightly smaller diameter than the diameter of the tube (see Figure 4). This glass is retained between substantially L-shaped brackets 13 and 14 which are secured to the walls of the tube by means of bolts 15. Opposite the pipe 2, a second pipe 16 is mounted in an opening in the wall of the boiler and a lamp 17 is arranged within this pipe. As shown, the lamp is mounted in a socket 17 arranged on the end of a pipe or conduit 18. The conduit is supported centrally of the pipe by suitable supporting members 19. Electric feed wires 20 extend through the conduit to the lamp socket. The end of this pipe is closed by a cap 21 having a plurality of openings 22 formed therein (see Figure 7).

In Figure 5 of the drawings, I have shown the attachment applied to two boilers arranged in series. The boilers are provided with outer walls 23 and are separated from each other by an inner wall 24. The inner wall is provided with two transverse openings 25 each having a pipe 26 arranged therein, and is further provided with a longitudinal opening extending through the back of the boiler to the openings 25. The pipe 16 is arranged in this opening and the lamps 17 are supported in the pipes in the manner described, each being disposed in alignment with one of the transverse open-

ings 25, as shown in Fig. 9. Mirrors are arranged in the two outer walls 23 in alignment with the openings 25, the construction of the mirror support being the same as in 5 the form of the invention heretofore described.

In Figure 6 of the drawings, the attachment is shown applied to the smoke stack 27 of a boiler and as shown, the smoke stack 10 communicates with the gas outlet through passages 28 and is provided with a damper 29 in the usual manner. The light 17 is supported in a tube 30, arranged in an opening 15 in the stack and the mirror support is likewise arranged in an opening in the stack opposite the lamp support.

The operation of the device will be apparent from the foregoing description. The 20 mirror and light are set in the wall of the boiler on opposite sides near the flue gas outlet and the gas passing between the mirror and light absorb or deflect the rays of light from the light element. The amount of this deflection is observed in the mirror 25 and as the deflection bears a certain ratio to the required air supply, the proper proportions can be determined by this observation. By observing the density or haze point of the gas leaving the boiler, the conditions under 30 which the boiler is operating may be readily determined. It is well known that when the minimum air supply has been reached, a small amount of haze will appear at the gas outlet. A bright light on the 35 mirror indicates excess air and a dark mirror will indicate insufficient air. The minimum air supply to support complete combustion has been reached when a red light is reflected on the mirror.

40 By providing a glass or lens 12 in the tube slightly smaller in diameter than the tube, the passage of air through the sight tube and the mirror casing is permitted at all times which keeps the mirror clean.

45 Likewise, the provision of holes 22 in the cap

21 permits a slight amount of air to pass through the tube 16 and keep the lamp clean. The mirror may be adjusted by means of the screws or studs 11 to compensate for mis-alinement in the installation or movement of the boiler walls.

By providing an attachment for each boiler, improper conditions may be immediately located where a number of boilers are connected to the same smoke stack. Under 55 ordinary conditions, one boiler of a series may get out of adjustment and produce considerable loss of fuel oil before it can be determined which boiler is causing the trouble.

It is to be understood that the forms of 60 my invention herewith shown and described are to be taken as preferred examples of the same and that various changes in the shape, size, and arrangement of parts may be resorted to without departing from the spirit 65 of the invention or the scope of the subjoined claim.

Having thus described my invention, I claim:

An attachment for oil fired burners having 70 a gas outlet provided with oppositely arranged aligned horizontal openings communicating therewith comprising a lamp supporting member arranged in one of said openings, a mirror casing arranged in the other 75 of said openings, a mirror holder mounted in said casing, a threaded pin carried by said mirror holder substantially centrally thereof and projecting loosely through said casing, a nut mounted on said pin, adjusting 80 means carried by said casing and contacting with the outer portions of said mirror holder, a mirror mounted in said holder and adapted to reflect rays of light from a lamp in said lamp supporting member and a sight 85 tube communicating with said mirror casing.

In testimony whereof, I affix my signature.

WINNFIELD RUSSEL PENDER.
